UNITED STATES PATENT OFFICE.

MARION S. PARSONS, OF JOPLIN, MISSOURI.

PUMP-CYLINDER.

1,281,412.

Specification of Letters Patent. Patented Oct. 15, 1918.

Application filed March 11, 1918. Serial No. 221,754.

To all whom it may concern:

Be it known that I, MARION S. PARSONS, a citizen of the United States, residing at Joplin, in the county of Jasper and State 5 of Missouri, have invented a new and useful Pump-Cylinder, of which the following is a specification.

The device forming the subject matter of this application is a pump of that general 10 type in which a pair of oppositely moving pistons work in a barrel, the packings being fixed with respect to the barrel, and one object of the invention is to provide a novel means whereby the packings may be manipulated readily to cause the same to coact 15 with the pistons.

Another object of the invention is to provide a novel form of barrel which may be fashioned in a continuous length, means 20 being provided, at the same time, whereby the packings may be adjusted and compressed as aforesaid.

Other and further objects will be made manifest in the closing portion of this specification, after the structure has been described in detail.

With the above and other objects in view which will appear as the description proceeds, the invention resides in the combination 30 and arrangement of parts and in the details of construction hereinafter described and claimed, it being understood that changes in the precise embodiment of the invention herein disclosed can be made within 35 in the scope of what is claimed without departing from the spirit of the invention.

In the accompanying drawings:—

Figure 1 shows in longitudinal section, a device constructed in accordance with the 40 present invention, parts appearing in elevation;

Fig. 2 is a cross section on the line 2—2 of Fig. 1; and

Fig. 3 is a cross section on the line 3—3 45 of Fig. 1.

In the accompanying drawings, the numeral 1 denotes a barrel having any desired number of openings 2 alined transversely of the barrel. Disposed within the barrel 1, above and below the openings 2 are annular 50 abutments 3 held in place by countersunk securing devices 4 of any desired sort. Packing rings 5 coact with the abutments 3 and are engaged by retaining rings 6. U-shaped compression members 7 extend into 55 the barrel 1 through the openings 2 and are

provided with broadened feet 8 which bear against the retaining rings 6, those portions of the barrel 1 which lie immediately above and below the openings 2 being received in 60 the compression members. The compression members 7 are supplied, externally of the barrel 1 with outwardly projecting lugs 9. Screws 10 are oppositely threaded into the lugs 9 of the compression members and 65 are supplied intermediate their ends with wrench heads 11 whereby the screws may be rotated.

Tubular pistons 12 work within the packing rings 5, there being any desired number 70 of the pistons. The valves in the pistons may be variously constructed without jeopardizing the utility of the invention, but by way of illustration, the pistons 12 are shown as being provided at their lower ends 75 with annular seats 14 with which coöperate vertically moving valves 15. Spiders 17 are removably mounted in the upper ends of the pistons 12. A rod 18, preferably in the form of a tube, is connected with the spider 80 of the upper piston, a rod 19 being mounted to slide in the member 18, the rod 19 being secured to the spider of the lower piston. The valve 15 in the present embodiment of 85 the invention (which is not mandatory) is shown as being mounted to reciprocate vertically on the rod 19.

Suitable means (not shown) are provided whereby the pistons 12 operate simultaneously in opposite directions. When the lower 90 piston moves downwardly, the valve 15 of the lower piston opens and admits the liquid. When the lower piston moves upwardly, the valve of the said piston closes, the upper piston moves downwardly, the valve in the 95 upper piston opens, and the liquid is received in the upper piston. Then the lower piston moves downwardly to receive a fresh charge, the liquid in the upper piston and in the barrel thereabove is raised, in a way which 100 will be understood readily by those skilled in the art when Fig. 1 is examined. By rotating the screws 10, the compression members 7 may be forced apart, thus causing the retaining rings 6 to compress the 105 packing rings against the abutments 3, the packing rings being forced, in this way, to engage the pistons 12 closely. The operation above alluded to can be carried out from a point exterior to the barrel 1.

The cylinder and the pistons are so constructed that the packings of the pistons

may be adjusted from the exterior of the barrel without removing any working parts. The construction shown is well adapted for use in pumping gritty water and under all 5 conditions wherein the packing is subjected to severe usage. The pistons are so arranged that an unusually long stroke is possible, the device being adapted to be used in deep installations, in mines and elsewhere. The 10 cylinder occupies, practically, no more space than does a cylinder of ordinary construction. The pistons 12 may be raised to the openings 2, for the purpose of examination, to permit the removal of lodged obstruc- 15 tions, and to facilitate the adjustment or re- placing of the valves. The weight of the water column is made effective to control the valves, and springs are unnecessary. The cylinder 1 may be made without joints of 20 any kind, the advantages incident to such a construction being obvious. A continuous upward flow of the liquid is secured, and at the same time the column of liquid above 25 the upper piston imposes no weight on the lower piston when the latter moves downwardly.

Since the compression members 7 are slidably mounted on the barrel 1 at the upper and lower edges of the openings 2, and 30 since the compression members are connected by the screws 10, it will be obvious that the compression members and the screws form a structure which will adjust itself vertically and produce an even and distributed pres- 35 sure on the packing rings 5 which are disposed above and below the openings 2.

Having thus described the invention, what is claimed is:—

1. In a pump, a barrel having openings; 40 abutments in the barrel above and below the openings; packings coöperating with the abutments; compression members extended through the openings and coacting with the packings; means assembled with the com-

pression members and located exteriorly of 45 the barrel for producing relative movement between the compression members longitudinally of the barrel; and a piston working in the packings.

2. In a pump, a barrel having openings; 50 abutments in the barrel above and below the openings; packings coöperating with the abutments; compression members extended through the openings and coacting with the packings; screws disposed exteriorly of the 55 barrel and right-and-left-hand-threaded into the compression members; and a piston mounted to reciprocate in the packings.

3. In a pump, a barrel having openings; 60 abutments in the barrel above and below the openings; packings coöperating with the abutments; U-shaped compression members extended through the openings and slidably mounted on the barrel at the upper and lower edges of the openings, the compression 65 members coacting with the packings; and adjustable connections uniting the compression members exteriorly of the barrel.

4. In a pump, a barrel having openings; 70 abutments in the barrel above and below the openings; packings coacting with the abutments; retaining rings engaging the packings; U-shaped compression members extended through the openings and engag- 75 ing the retaining rings, the compression members being slidably mounted on the barrel at the upper and lower edges of the openings; and screws located exteriorly of the barrel, the screws being right-and-left- hand-threaded into the compression mem- 80 bers.

In testimony that I claim the foregoing as my own, I have hereto affixed my signature in the presence of two witnesses.

MARION S. PARSONS.
